STEM FOR TOBACCO PIPES AND THE LIKE

Herman W. Fisher, Philadelphia, Pa.

Application January 31, 1955, Serial No. 484,976

2 Claims. (Cl. 131—210)

This invention relates to an improved stem construction for tobacco pipes or the like.

The principal object of the invention is to provide a stem construction which will remove from tobacco smoke a large percentage of the tars, nicotine, moisture or other objectionable products which it carries in suspension before it reaches the smoker's mouth. It is also an important object of the invention to adequately cool the smoke in its transit through the stem.

A still further object is to provide a baffling arrangement for the smoke in which the smoke must pass under and over a series of baffle plates having a trap-like well below each baffle under which the smoke passes. Another object is to provide a baffle chamber having a bottom access opening over which a suitable closure cap can be placed, which cap has resilient means for holding it in position, the cap when in its proper position being arranged to contact the bottom edges of any baffle which provides an overpass for the smoke. A further object is to provide a baffle and well construction of the type described in which moisture incident to the burning of the tobacco will be prevented from reaching the mouth and, vice versa, in which any moisture from the mouth will be prevented from reaching the point of combustion, the said moisture coming from both directions being trapped in the baffle chamber and absorbed upon an absorbent pad, if desired.

How the foregoing objects, together with any other objects which may hereinafter appear or are incident to my invention are attained, is illustrated in the accompanying drawings wherein Figure 1 is a vertical longitudinal section of my improved stem with the bowl of a pipe attached thereto, the bowl being shown in side elevation and the section being taken as indicated by the line 1—1 in Figure 2; Figure 2 is a bottom view of the structure of Figure 1; and Figure 3 is a vertical transverse section taken as indicated by the line 3—3 in Figure 1.

Examination of the figures of the drawing will show that my improved stem comprises a main body portion 4 having the usual bead 5 at the end which enters the smoker's mouth and a reduced extension 6 at the opposite end over which may be fitted the stem of a pipe bowl 7 or other like device for holding the tobacco product to be smoked.

Intermediate its ends but preferably somewhat closer to the reduced extension 6 than to the mouth bead 5, my improved stem is provided with an enlarged portion 8, the interior of which constitutes a baffle chamber 9 in which a plurality of baffles 10, 11 and 12 are arranged so that the smoke as it passes from the region of combustion to the mouth of the smoker must follow a tortuous path. In the embodiment illustrated this tortuous path is created by virtue of the fact that the baffles 10 and 12 are secured at their top and side edges to the main body structure of the chamber 8 so that they provide underpasses for the smoke as illustrated by the arrows 13 and 14. The other or mid-baffle 11 in the embodi-

ment illustrated is secured at its sides only and this baffle provides an overpass for the smoke as indicated by the arrow 15. In this connection it will be understood, of course, that the smoke from the region of combustion flows through a passageway 16 on its way to the mouth bead 5.

The baffle chamber 8 is constructed with a downwardly protruding extension 17 and it will be noted that the arrangement is such as to cause the smoke coming from the region of combustion to enter the baffle chamber at a point above the horizontal mid-region of the chamber and to leave the chamber at a diametrically opposite point so as to provide for a series of extended travel paths in the vertical direction. The lower end of the extension 17 is provided with an access opening as clearly shown in the drawings, which access opening is covered by cap member 18. The mid-baffle 11, which is fastened at its side edges only, is arranged so that its bottom edge lies in the same horizontal plane as the bottom face of the protruding extension 17. In this way when the cap is in its assembled position on the extension 17, it will contact the bottom edge of any baffle which provides an overpass for the smoke and thereby serve to create a trap-like well under the bottom edge of the baffles which provide underpasses for the smoke. At this point it should be noted that while I have illustrated three baffles in the present embodiment, it should be understood that a greater number of baffles may be employed, if desired. The more baffles, of course, the cooler and drier will the smoke be by the time it reaches the smoker's mouth.

The cap is formed preferably as a one piece, slightly resilient plastic member which has an inwardly extending ridge or bead-like flange 19 adapted to firmly grip the sides of the protruding extension 17 and to hold the cap by frictional contact in its proper position, the arrangement being such as to effect tight closure at this point for the exclusion of air.

Before the cap is placed in position, there can be placed in its bottom portion, if desired, a relatively thin pad 20 of some suitably absorbent material, which is designed primarily to soak up the moisture. It should be understood, however, that such an absorbent pad is not essential to a realization of the principal advantages of my improved stem although its use will minimize the number of times that the cap must be removed for cleaning purposes.

Inasmuch as the cap 18 is held in place by virtue of a resilient frictional engagement with the sides of the extension 17, it can be quickly and easily removed when it is desired to clean out the chamber.

I wish to call attention to the fact that with my improved construction the stem with all of the baffles employed can be made either as a single piece or with all of the baffles secured firmly to the body of the stem. This provides a very strong construction and also a very simple one inasmuch as there is but a single removable part, namely, the cap member.

The smoke is dried and cooled by virtue of its long travel through the baffle chamber and much of the deleterious products of combustion are trapped in the series of wells in the lower portion of the chamber, thereby yielding a smoke which is far cleaner than it otherwise would be. Furthermore, the pipe bowl remains relatively free of incrustations because of the fact that the moisture is removed and trapped in the wells and can not flow back into the bowl. Also, the fact that there is little or no moisture in the bowl, keeps the tobacco from becoming soggy and enables it to burn to a fine ash. In addition to the foregoing advantages my improved stem construction makes it a very easy task to clean the pipe and this can be done without the need of a pipe cleaner

simply by removing the bowl and the closure cap and flowing water therethrough.

I claim:

1. A smoker's pipe stem or similar device having a baffle chamber interposed in the passageway for the smoke, said chamber having a plurality of baffle plates extending cross-wise of the axis of the passageway and arranged so that the smoke must follow a tortuous path through the chamber alternately under and over the plates, and the bottom of the chamber having an access opening and a readily removable closure cap for said access opening, any one of said baffle plates which provides an underpass for the smoke being secured to the walls of the chamber at the top and at the sides and any one of said baffle plates which provides an overpass being secured at the sides, and said stem with its chamber and baffle plates being formed as a unitary piece.

2. A smoker's pipe stem or similar device having a baffle chamber interposed in the passageway for the smoke, said chamber being constructed with a downwardly protruding extension having an access opening at the bottom thereof, a plurality of baffle plates extending cross-wise of the axis of the passageway and arranged so that the smoke must follow a tortuous path

through the chamber alternately under and over the plates, any one of said baffle plates which provides an underpass for the smoke being secured to the walls of the chamber and any one of said baffle plates which provides an overpass being arranged with its bottom edge lying in the same horizontal plane as the bottom face of the protruding extension, and a readily removable closure cap for the access opening adapted to cooperate with the bottom face of the protruding extension and with the bottom edge of any overpass baffle to provide a trap-like well under the bottom edge of any underpass baffle.
